COMBINED SPOUT AND CONTROL PANEL

Jack N. Kaiser, Louisville, Ky., assignor to American Standard Inc., New York, N.Y., a corporation of Delaware

Filed Apr. 23, 1969, Ser. No. 16,860

Term of patent 14 years

Int. Cl. D23—01

U.S. Cl. D23—26

Fig. 1.

Fig. 2.

Fig. 3.

Fig. 4.

FIG. 1 is a front elevational view of a combined spout and control panel showing my new design;

FIG. 2 is an elevational view taken from the left end thereof;

FIG. 3 is a cross sectional view taken on line 3—3 of FIG. 1; and

FIG. 4 is a front perspective view thereof.

I claim:

The ornamental design for a combined spout and control panel, substantially as shown.
